WARE

STOKER CONTROL

Application filed May 6, 1931. Serial No. 535,406.

The object of my invention is to provide an improved control apparatus for stoker fed furnaces by means of which successive charges of fuel will be delivered to the furnace in response to temperature demands of the space to be heated, the periodicity and extent of such fuel delivery periods being variable, and by means of which fuel charges of predetermined amounts may be automatically delivered to the furnace, in the absence of temperature demand in the space to be heated, at a predetermined interval of time next following a preceding fuel charge whether such preceding fuel charge was in response to room temperature demand or in response to lapse of time in the absence of room temperature demand.

The accompanying drawings illustrate my invention:

20 Fig. 1 is an elevation in partial vertical section of a special switch-controlling unit, the details of construction of which are not original with me.

25 Fig. 2 a fragmentary section in the plane of the rotor shaft of the motor;

Fig. 3 a section on line 3-3 of Fig. 1;

Fig. 4 a section on line 4-4 of Fig. 1;

Fig. 5 a section on line 5-5 of Fig. 3;

Fig. 6 a fragmentary section in the plane of Fig. 3 with the latch mechanism in the positions assumed when the driving pawl is held retracted;

Fig. 7 a fragmentary section on line 7-7 of Fig. 1; the parts being shown in an advanced position.

Fig. 8 a fragmentary section on line 8-8 of Fig. 1;

Fig. 9 a section on line 9-9 of Fig. 1; and

40 Fig. 10 a wiring diagram.

In the drawings 10 indicates a suitable supporting frame in which is mounted a power-receiving shaft 11 and a power delivery shaft 12 with an intermediate speed-reducing train 13 of any desired character. Shaft 11 is conveniently the rotor shaft of an electric motor 14 and this shaft carries a flange 15 upon which are pivoted two arc-shaped friction shoes 16 which lie within a stationary shell 17. The shoes 16 are so

formed that, when shaft 11 is rotating at full speed, said shoes will hug the shaft but, as the speed of shaft 11 drops below normal, said shoes, as they pass beneath the shaft, will drag upon the inner surface of 55 the stationary shell 17 which encloses the shoes, said shoes thus having a braking effect to hasten stoppage of the motor.

The power delivery shaft 12 carries a pinion 20 which meshes with a gear 21 journaled upon a stud pin 22 supported upon frame 10 and gear 21 carries a hardened ratchet ring 23 provided with ratchet teeth 24.

Journalled upon stud 22 is a sleeve 25 65 which is to be automatically oscillated through various arcs from an initial position by the mechanism now to be described.

Secured to that end of sleeve 25 adjacent gear 21 is a plate 26 having a pin 27 projected into a spring chamber 28 formed in gear 21. Pin 27 forms the anchorage for one end of a volute spring 29 nested in chamber 28 and having its inner end attached, at 30, to stud 22. 75

In order to set spring 29 at any desired tension stud 22 is journalled, at 31, in frame 10 and may be held in any desired position of angular adjustment by nut 32 threaded on to stud 22 and engaging frame 10. 80

Journalled in plate 26 is a pawl shaft 35 carrying, at one end, a pawl 36 overlying and adapted to engage the ratchet teeth 24, and carrying at the other end a lever 37, the parts 35, 36 and 37 being secured together to oscillate as a unit about the axis of shaft 35.

Journalled upon shaft 35, between lever 37 and plate 26, is a pawl-retracting lever 38 having a latch finger 39. Lever 37 is provided with a laterally-extended finger 40 which overlies and has a one-way engagement with lever 38, being normally yieldingly retained in engagement with lever 38 by a spring 41 anchored at 42 on lever 38 and engaging lever 37 at 43. Lever 37 is provided with a latch finger 44 with which cooperates a shoulder 45 of a latch lever 46 pivoted at 47 on plate 26. Also pivoted at 47 is a latch lever 48 having a latch shoul- 95 100

der 49 adapted to cooperate with finger 39 of lever 38. Lever 46 is urged in a counter clockwise direction (Fig. 3) relative to lever 48 by a spring 8, one end of which is anchored at 50 on latch 46 and the other end of which is anchored on a pin 51 on latch lever 48, said pin 51 serving as a stop to limit counter-clockwise movement of lever 46 relative to lever 48. Latch lever 48 is 10 provided with a finger 52 which overlies, and under some conditions is adapted to engage, lever 38, in one direction, to shift said lever in a clockwise direction. Lever 48 is 15 yieldingly urged in a clockwise direction by a spring 54 anchored at 55 on plate 26. Lever 38 is yieldingly urged in a clockwise direction by a spring 56 anchored at 57 on plate 26.

When pawl 36 is in effective position relative to the ratchet teeth 24, the parts are 20 in the positions shown in Fig. 3, at which time finger 39 of lever 38 is restrained in its uppermost position by resting upon shoulder 49 of lever 48; finger 44 of lever 37 25 lies under lever 46 with its end free from shoulder 45 of lever 46; and finger 40 of lever 37 lies in engagement with lever 38.

Journalized upon sleeve 25 is a ratchet disc 60 provided with a segmental series of ratchet teeth 61. Disc 60 is provided with pin 62 (Fig. 4) which is projected into the plane of lever 48 beyond its axis so as to be capable of swinging lever 48 in a counter-clockwise direction. Ratchet disc 60 is also provided with a pin 63 projected into the plane of lever 38 and adapted to move said lever, against the action of spring 56, in a counter-clockwise direction.

The pin 62 is carried by a projecting finger 40 60' of disc 60 and projected into the path of movement of this finger is a stationary finger 65 carried by the frame 10 to limit the movement of disc 60 in a clockwise direction.

Movement of disc 60 in a counter-clockwise direction is limited by a stationary pin 66 carried by frame 10.

Splined upon sleeve 25 is a sleeve 70 upon which are sleeved a plurality of switch-actuating cams 71, 72, 73, with interposed 50 spacers 74 and held in relative angular adjustment by a nut 75 threaded upon the outer end of sleeve 70. The locking nut 76, threaded upon the outer end of sleeve 25 55 serves to hold sleeve 70 in place against shoulder 77 of sleeve 25 and also serves as a locking nut for the nut 75.

A spring 79, anchored at one end on pin 80 carried by sleeve 70 and at the other end on pin 81 carried by ratchet disc 60, 60 serves to normally hold pin 62 in engagement with lever 48.

In Fig. 3 the parts are shown in the positions occupied when disc 60 has been advanced nearly to the limit of its forward 65 stroke, pin 62 being at that time in engage-

ment with pin 65. Further advancement, in clockwise direction, of gear 21 and plate 26 will, because of the engagement of pin 62 with lever 48, cause said lever to swing upon its pivot against the action of spring 54 70 so as to withdraw shoulder 49 from beneath finger 39 of lever 38, whereupon, spring 56 will swing lever 38 clockwise to initial position.

The left hand arm of lever 46, during the 75 major portion of the above-mentioned movement of lever 48 is obstructed by finger 44 of lever 37. When shoulder 49 is fully retracted from finger 39 of lever 38, said lever will be released and swung in a clockwise direction by spring 56, the lever 38 positively retracting pawl 36 from the ratchet teeth 24, at the same time shifting finger 44 to the left to permit shoulder 45 of lever 46 to drop down behind it to definitely lock 80 pawl 36 in a retracted position relative to the ratchet teeth.

Plate 26 is thus released from driven connection with gear 21 and spring 29 acts to return said plate, and the connected cam sleeve unit, to initial position finger 60' 90 coming into engagement with stop pin 66 and the inner end of lever 38 coming into engagement with stop pin 63, shortly after finger 60' has been stopped by finger 66. 95 The engagement of lever 38 with stop pin 63 swings said lever in a counter-clockwise direction so as to restore its finger 39 to permit notch 49 of lever 48 to swing to locking position beneath finger 39 and this movement brings pin 51 of lever 48 into engagement with latch lever 46 to retract its shoulder 45 from finger 44 of lever 37, thus permitting spring 41 to restore engagement 100 of pawl 36 with teeth 24.

In order that the cam unit may be automatically restored to initial position from any selected point in its travel I provide a pawl 90 pivoted at 91 on one arm of a lever 92. This pawl is normally urged inwardly 110 to engagement with the ratchet teeth 61 of disc 60 by a spring 93 and this spring-urged movement relative to lever 92 is limited by stop pin 94 carried by lever 92.

The other end of lever 92 is connected by 115 link 95 with a lever 96 which carries the armature 97 of a relay 98 which, when energized, serves to drive pawl 90 in a direction to angularly shift disc 60 a distance sufficient to cause its pin 62 to actuate lever 48 120 in the same way that said lever is actuated when finger 60' is stopped by stop finger 65, so as to retract pawl 36 from teeth 24. Armature 97 is normally biased away from the core of coil 98 by a counter-weight 97'. 125

It is desirable that pawl 90 be incapable of actuating disc 60 for a short period immediately following advancement of this disc from its initial position and consequently the angular extent of the series of 130

teeth 61 is such that the initial end of this series of teeth does not come opposite pawl 90 until the advancement of the disc 60 from its initial position has continued for a pre-determined period, say about ten minutes if the gear train 12 is such that the total movement of disc 60 will require a period of an hour, more or less.

In order that the pawl 90 may not offer frictional resistance to forward movement of disc 60, it is held normally retracted from the ratchet teeth by a stop pin 99.

The one-way engagement between levers 37 and 38 permits the necessary freedom of ratchet 36 relative to teeth 24.

Failure of any one of the springs would not permit damage of the apparatus due to an excessive forwarding action of the ratchet drive because, finger 60' being positively driven against stop pin 65, pin 62, engaging lever 48, will swing it counter-clockwise to drive its finger 52 against lever 38, which, moving clockwise and engaging finger 40, will retract pawl 36 from ratchet teeth 24 so that the motor may proceed without damage to the apparatus. If spring 29 has become ineffective the parts will remain in their most advanced position; if spring 41 has become ineffective, the coaction of pawl 36 with teeth 24 through said range will be ineffective; if either of springs 54 and 56 has become ineffective there will be merely a delayed coaction between levers 38 and 48.

The mechanism which has been described above is conveniently supported upon a bakelite base 100. Mounted upon base 100 below the cam shaft is mounted a shaft 101 upon which are supported three spring-urged rocking brackets 102, 103 and 104 carrying fingers 105, 106 and 107 arranged to be contacted respectively by the cams 71, 72 and 73. Bracket 102 carries a bakelite arm 108 to which is secured a spring terminal 109 arranged, when permitted by cam 71, to contact with the terminal 110 carried by suitable insulating support. Bracket 103 carries a bakelite arm 111 which carries the spring terminals 112 and 113, terminal 113 being projected through the body of terminal 112, as shown in Fig. 8. The terminals 112 and 113 are electrically-connected and are arranged to contact, when permitted by cam 72, with terminals 114 and 115 respectively, which terminals are electrically-insulated from each other.

Bracket 104 carries a bakelite arm 116 upon which are mounted the spring terminals 117 and 118 electrically isolated from each other and arranged to contact, when permitted by cam 73, with terminals 119 and 120 respectively, the terminal 118 coming into contact with terminal 120 slightly before terminal 117 contacts with its terminal 119.

Cams 71, 72 and 73 are so formed and

positioned, that, when the fly-back mechanism is in its initial position terminals 109, 112, 113, 117 and 118 will be in contact with their respective terminals 110, 114, 115, 119, and 120. Advancement of the cam shaft 70 will first bring cam 73 into engagement with finger 107 to retract terminals 117 and 118 in succession from their cooperative terminals and to permit resumption of contact a very short interval thereafter. Cams 71 and 72 are so formed as to hold their associated terminals out of contacting position for a major portion of the cam cycle.

The armature arm 97 carries three spring terminals 125, 126 and 127 coacting respectively with terminals 128, 129 and 130, the arrangement being such that 126 contacts with 129 when relay 98 is deenergized and 125 and 127 contact respectively with 128 and 130 when the relay 98 is energized.

Turning now to the wiring diagram Fig. 10. A room thermostat R of well known form is installed in a room to be heated. This thermostat conveniently comprises a bimetallic blade 135 having contact fingers 136 and 137 electrically connected with blade 135 and arranged to contact respectively with terminals 138 and 139, 137 contacting with 139 slightly in advance of the contact between 136 and 138. Terminal 128 is connected to line wire 143.

A transformer T has its primary 140 connected by wires 141 and 142 with the line wires 143 and 144 respectively. The secondary 145 of transformer T has one end connected by wire 146 with one end of relay coil 98 and this wire is connected through rheostat RH with the field of the timer motor 14, the other end of said field being connected by wire 147 with terminal 126 and terminal 109. The other end of the secondary 145 is connected by wire 148 with terminal 120 and also with one terminal 149 of a temperature-responsive circuit-controlling switch S, commonly known as a "stack control" or "combustion-controlled switch" which is placed at a point where it will be promptly affected by combustion conditions in the furnace; the other terminal 150 of the stack control S is connected by the branched wire 151 with terminals 118, 110, 139, 115, and 129. Blade 135, and its associated contact fingers 136 and 137, of the room thermostat R, is connected by a wire 152 with terminals 127 and 112 and 113. One end of relay coil 98 is connected by the branched wire 153 with terminals 130, 138 and 119. Terminals 114 and 117 are connected by wire 154.

The stoker motor M is connected by wire 155 with the line wire 144, and by wire 156 with terminal 125.

Diagram Fig. 10 shows the circuit condition at the time when the cam shaft 70 is in its initial, or re-cycled position, and assuming the room thermostat to be satisfied and

therefore open, coil 98 is energized through the circuit: 145, 146, 98, 153, 119, 117, 154, 114, 112, 113, 115, 151, 118, 120, 148, 145, thus closing contacts at 127—130 and 125—128. The closing of a circuit through the secondary 145 permits current flow through the primary 140 and, contacts 125—128 being closed, the stoker motor M is energized through the circuit 144, 155, M, 156, 125, 128, 143. The timer motor is energized through the circuit 145, 146, RH, 14, 147, 109, 110, 151, 118, 120, 148, 145, and as soon as there is a temperature increase in the fire a parallel is established through 150—149. Adjustment 15 of the rheostat RH will vary the speed of the timer motor and thus change the length of the time cycle.

Forward movement of the cams for a predetermined interval, brings cam 73 into position to first withdraw terminal 117 from terminal 119, thus opening the initial energizing circuit of the coil 98 but not disturbing the holding circuit described above. If, during this interval, there has been an increase 25 in temperature of the fire, 150 will have been contacted with 149, thus providing the circuit 145, 146, RH, 14, 147, 109, 110, 151, 150, 149, 148, 145, to keep the timer motor in movement. Further slight advance of cam 73 30 moves 118 away from 120, so that, if contact at 150—149 has not been established by increase of furnace temperature, the holding circuits through 98 and 14 are not established and further operation of the stoker 35 motor and timer motor is stopped because the release of the relay 98 opens the stoker motor circuit at 125—128 and the timer motor circuit is open at 118—120 so that further operation cannot be obtained until the fire is re-kindled.

If there has been a proper response of stack control S to fuel delivery under these circumstances, the forward movement of the timer motor continues and fuel delivery continues until cam 72 separates 113 from 115, whereupon the circuit through the relay coil 98 is broken, the relay armature released, and the circuit of motor M broken at 125—128. Further advance of the cams opens a gap at 50 109—110 but, the release of the relay 98 having established contact at 126—129, the timer motor continues to be energized through the circuit 145, 146, RH, 14, 147, 126, 129, 151, 150, 149, 148, 145, and proceeds to the end 55 of its cycle where 62 causes movement of 48 (Fig. 3) to release the snap-back mechanism, in the manner previously described to recycle the apparatus.

It will be noted that cam 73 is a short cam 60 which serves to separate terminals 117 and 118 from their respective terminals 119 and 120 for only a short period in a cycle and that cams 71 and 72 are longer cams serving to separate terminals 109, 112 and 113 from 65 their respective terminals 110, 114 and 115

at times when terminals 117 and 118 are in contact with their respective terminals 119 and 120. Terminal 150 is quite likely to separate from 149 at some time during a timing cycle but, if 98 has been deenergized, such separation will not of itself cause a stoppage of the timer motor because an energizing circuit is established for it through 118—120 (which is reestablished by cam 73 shortly after it is broken) and through 126—129, as already stated. Terminal 112 separates from 114 shortly before 113 separates from 115, thus avoiding any chattering.

Whenever the room thermostat R calls for heat by contacting terminals 136 and 137, with their respective terminals 138 and 139, relay coil 98 is initially energized through the following circuit: 145, 146, 98, 153, 138, 136, 137, 139, 151, 118, 120, 148, 145 and operates to close the gaps at 127—130, and 125—128, and open a gap at 126—129, thus completing the circuit of motor M as already described. The closing of the gap at 127—130 completes a holding circuit for the relay 98 as follows: 145, 146, 98, 153, 130, 127, 152, 135, 137, 139, 151, 118, 120, 148, 145. Energization of relay 98 always recycles the apparatus except during the period of initial forwarding of disk 60 when there are no teeth 61 to be engaged by pawl 90.

If the call for heat by the room thermostat is initiated before, and continues after, cam 71 opens the circuit gap at 109—110, the opening of this gap serves to stop the timer motor 14 because of the break in the circuit 145, 146, RH, 14, 147, 109, 110, 151, 150, 149, 148, 145, but, as already pointed out, the relay coil 98 being energized through a circuit controlled by the room thermostat, the stoker motor circuit through 125—128 is preserved and fuel delivery continues until the room thermostat is satisfied, whereupon, the relay circuit being broken, the stoker motor circuit is broken at 125—128, and the timer motor circuit 145, 146, RH, 14, 126, 129, 151, 150, 149, 148, 145, is established so that the timer motor carries the snap-back apparatus on to the end of its cycle.

If there is a call for heat by the room thermostat after cam 71 has opened the circuit gap at 109—110, cam 72 has opened circuit gaps at 112—114 and 113—115 and cam 73 has opened, but again closed, circuits at 117—119 and 118—120. Consequently when the room thermostat brings both of its fingers 136 and 137 in contact with their respective terminals 138 and 139, the initial energization of 98 is accomplished through the circuit 145, 146, 98, 153, 138, 136, 137, 139, 151, 118, 148, 145, establishing the stoker motor circuit at 125—128 and the relay holding circuit at 130—137. Energization of the relay causes pawl 90 to trip the snap-back 125 130

mechanism to permit its return to initial position, thus recycling the apparatus.

At this point we call attention to the fact that the stack control S is preferably of that well known type wherein separation of terminal 150 from 149 takes place promptly upon decrease of temperature and re-establishment of contact is accomplished promptly upon increase of temperature, irrespec- 10 tive of absolute temperature, so that at an early stage in each fuel delivery period the element S stands guard to throw the apparatus automatically out of commission if there is a drop in temperature or there fails 15 to be a prompt rise in temperature immediately following the beginning of each fuel delivery.

It will be noted therefore that the apparatus has the following characteristics:

20 So long as the room thermostat is satisfied there will be recurrent deliveries of fuel for predetermined periods equally spaced.

Any call for heat by the room thermostat, overlapping a time-period fuel delivery, results 25 in a stoppage of the timer motor while fuel delivery persists under the call of the room thermostat until it is satisfied, whereupon the timer motor proceeds to the end of the cycle of the snap-back mechanism so 30 that, in the absence of a succeeding call for heat by the room thermostat, during the remainder of the cycle, a predetermined time will elapse before there will be another time-period fuel delivery.

35 The apparatus is always (providing there is an existing fire), responsive to a room thermostat call for heat and whenever that call comes (except during the very short time when cam 73 is functioning to produce 40 circuit gaps at 117-119 and 118-120) the snap-back mechanism is automatically recycled, so that each fuel delivery, whether it be in response to lapse of time or in response to room thermostat control, occurs at the beginning 45 of the newly established time-period cycle. Consequently each time-period fuel delivery occurs only after the lapse of a predetermined time following the last preceding fuel delivery whether that fuel delivery has 50 been in response to lapse of time or room thermostat call.

When the apparatus has been thrown out of commission, due to production of circuit gaps at 117-119 and 118-120 when a circuit gap exists at 149-150, the apparatus 55 must be manually recycled and, of course, this recycling would not be accomplished until after the fire had been re-kindled so that 150 would be contacted with 149. The 60 manual recycling is accomplished by manipulation of the finger piece 200 (Fig. 4), which will cause pawl 90 to recycle the snap-back mechanism and establish a holding energizing circuit for relay 98 through 130- 65 127, as already described, whereupon the ap-

paratus is put back into condition for continued automatic operation.

The fundamental results attainable by the operations of the above-described apparatus, i. e., the energization of a fuel-feeding device at irregular intervals, depending upon the needs of a space to be heated and upon the call of a timed element, by means of a circuit-controlling element which is automatically recycled at each call for fuel, either by the time-train or by heat demand, have been accomplished by others and, therefore, my invention resides in the provision of certain variable circuit relationships, in a recycling mechanism of the described character, by means of which there will be automatically established desirable holding circuits for the relay which controls energization of the fuel motor so that, an initiating circuit having been established for the relay, in response to any call for fuel, there will also be provided a relay holding-circuit which is controlled by a contact which, itself, is incapable of completing the initiating circuit, thus insuring reliability of ac- 90

tion. Terms found in the claim are defined as follows: "room thermostat", a dual-circuit thermally-responsive switch having a blade contacting two independent contacts in succession and bridging the same; "first timer-controlled switch", a dual-circuit mechanically operated switch having two blades contacting two independent contacts in succession; "second timer-controlled switch", a 100 dual-circuit mechanically operated switch having a blade contacting two independent contacts in succession and bridging the same; "third timer-controlled switch", a single-circuit mechanically-operated switch; "timer-motor", an electric motor actuating the three mechanically operated switches; "combustion-controlled switch", a single-point, thermally-responsive switch alternately making and breaking contact upon reversals of temperature; "relay", an electrically-operated switch having three electrically-independent contacts controlling three circuits two of which are contacted when the relay coil is energized and the other contacted when the relay coil is de-energized; "recycling driving train", a driving connection between the timer motor and the switches actuated thereby such that the switch-actuating mechanism may be automatically returned to initial position at the end of a predetermined stroke or from intermediate positions.

I claim as my invention:

1. A stoker-controller comprising an electric timer-motor, an energy source, a room thermostat, a combustion-controlled switch, a relay embodying three electrically-independent switch elements two contacting and the other breaking upon relay energization, 125 130

an energizing circuit for an electric motor to be controlled, a first timer-controlled switch, a second timer-controlled switch, a third timer-controlled switch, a recycling driving train between the timer-motor and the first, second and third timer-controlled switches, and circuit connections between the several parts whereby completion of circuits through the room thermostat energizes the relay to recycle the said first, second and third switches, operation of the timer motor manipulates its switches to cause timer motor continuance or stoppage depending upon condition of the combustion-controlled switch and timer-motor stoppage if and while the room thermostat calls for heat beyond normal time call and upon any energization of the relay a relay-holding circuit is thereupon established through contacts actuated by the timer motor which themselves cannot serve to establish initial relay energization.

2. A stoker-controller comprising an electric timer-motor, an energy source, a room thermostat, a combustion-controlled switch, a relay embodying three electrically-independent switch elements two contacting and the other breaking upon relay energization, an energizing circuit for an electric motor to be controlled, a first timer-controlled switch, a second timer-controlled switch, a third timer-controlled switch, a recycling driving train between the timer-motor and the first, second and third timer-controlled switches, and electrical connections between relay coil, source, room thermostat, first and second timer-controlled switch and one relay switch, and electrical connections between room thermostat, first and second timer-controlled switch, combustion-controlled switch, combustion-controlled switch and source, and electrical connections between source, timer-motor, third timer-controlled switch, one relay switch, room thermostat, first and second timer-controlled switch and combustion-controlled switch, substantially as and for the purpose described.

3. A stoker-controller comprising an electric timer-motor, an energy source, a room thermostat, a combustion-controlled switch, a relay embodying three electrically-independent switch elements two contacting and the other breaking upon relay energization, an energizing circuit for an electric motor to be controlled, a first timer-controlled switch, a second timer-controlled switch, a third timer-controlled switch, a driving train between the timer motor and the three timer-controlled switches capable of driving said switches through their cycles and to initial position, and circuit connections between the several parts whereby completion of circuits through the room thermostat energizes the relay to recycle the said first, second and third switches, operation of the

timer-motor manipulates its switches to cause timer-motor continuance or stoppage depending upon condition of the combustion-controlled switch and timer-motor stoppage if and while the room thermostat calls for heat beyond normal time call and upon any energization of the relay a relay holding-circuit is thereupon established through contacts actuated by the timer-motor which themselves cannot serve to establish initial relay energization.

4. A stoker-controller comprising an electric timer-motor, an energy source, a room thermostat, a combustion-controlled switch, a relay embodying three electrically-independent switch elements two contacting and the other breaking upon relay energization, an energizing circuit for an electric motor to be controlled, a first timer-controlled switch, a second timer-controlled switch, a third timer-controlled switch, a driving train between the timer motor and the three timer-controlled switches capable of driving said switches through their cycles and to initial position and electrical connections between relay coil, source, room thermostat, first and second timer-controlled switch and one relay switch, and between room thermostat, first and second timer-controlled switch, combustion-controlled switch and source, and electrical connections between source, timer-motor, third timer-controlled switch, one relay switch, room thermostat, first and second timer-controlled switch and combustion-controlled switch, substantially as and for the purpose described.

In witness whereof, I have hereunto set my hand at Wabash, Indiana, this 16 day of April, A. D. one thousand nine hundred and thirty-one.

PAUL F. SHIVERS.

CERTIFICATE OF CORRECTION.

Patent No. 1,911,773.

May 30, 1933.

PAUL F. SHIVERS.

It is hereby certified that error appears in the printed specification of the above numbered patent requiring correction as follows: Page 6, line 93, claim 4, after "and" insert the words "electrical connections"; and that the said Letters Patent should be read with this correction therein that the same may conform to the record of the case in the Patent Office.

Signed and sealed this 1st day of August, A. D. 1933.

M. J. Moore.

(Seal)

Acting Commissioner of Patents.
